US0D1095150S

(12) **United States Design Patent** (10) **Patent No.:** **US D1,095,150 S**
(45) **Date of Patent:** **** Sep. 30, 2025**

(54) **MIXING CONTAINER LID**

(71) Applicant: **GUANGZHOU QINGKUAI INNOVATION TECHNOLOGY CO., LTD.**, Guangdong (CN)

(72) Inventors: **Chuang Lin**, Guangdong (CN); **Dongyue Wang**, Guangdong (CN); **Hao Liu**, Guangdong (CN)

(73) Assignee: **GUANGZHOU QINGKUAI INNOVATION TECHNOLOGY CO., LTD.**, Guangzhou (CN)

(**) Term: **15 Years**

(21) Appl. No.: **29/980,402**

(22) Filed: **Dec. 24, 2024**

(30) **Foreign Application Priority Data**

Aug. 12, 2024 (CN) 202430509407.1

(51) **LOC (15) Cl.** **07-04**

(57) **CLAIM**

The ornamental design for a mixing container lid as shown and described.

DESCRIPTION

FIG. 1 is a perspective view of a mixing container lid showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the mixing container lid that form no part of the claimed design. The dot-dot-dash lines define the bounds of the claimed design and form no part thereof.

1 Claim, 8 Drawing Sheets
